UNITED STATES PATENT OFFICE.

MONNOSUKE HIGUCHI, OF COLLEGE POINT, NEW YORK.

MOVING-POCKET GAME APPARATUS.

Application filed November 4, 1922. Serial No. 598,990.

To all whom it may concern:

Be it known that I, MONNOSUKE HIGUCHI, a subject of the Emperor of Japan, residing at College Point, county of Queens, and 5 State of New York, have made a certain new and useful Invention in a Moving-Pocket Game Apparatus, of which the following is a specification.

This invention relates to amusement and 10 recreation apparatus, wherein a system of co-ordinating elements co-operate to automatically release a ball, or several balls in succession, to be put into play, and to automatically record a score made by a player 15 who puts the balls into play. A further object includes the provision of mechanism for constantly modifying the probable results of any particular play, including a multiple-pocket constantly-moving device 20 and a system of circuits, relays and operating devices for effecting the operating and recording mechanism.

Other objects will appear hereinafter, and I attain these objects by the mechanism 25 illustrated in the accompanying drawing, in which

Fig. 1 is a view partly in section, showing one form of ball tossing mechanism in relation to the moving pocket;

Fig. 2 is an isometric view of the ball moving pocket and cabinet;

Fig. 3 is a view, largely diagrammatic, of the operating circuits and tally recording parts;

Fig. 4 is a sectional view of the moving pocket and corresponding circuit closers;

Fig. 5 is a plan view of the pocket moving motor and reciprocator;

Fig. 6 is an elevation of the score registering mechanism;

Fig. 7 is a view of the coupon registering mechanism;

Fig. 8 is a view of the score or coupon registering escapement;

Fig. 9 is a view in perspective of the releasing detent;

Fig. 10 is a sectional view of the ball operating circuit closer; and

Fig. 11 is a view of the coin chute showing the circuit closing contacts.

Like numerals refer to similar parts throughout the several views.

Referring now to the accompanying drawing which is given by way of illustra-

tion rather than in a limiting sense, in a 55 fixed cabinet 15, of any desired shape and suitable size, a movable ball catching pocket element 16, operating motor 17, ball projecting device or trajectory tray 18, ball retaining mechanism and sloping base 19, 60 circuit closers 20, and associated contactors, are provided for the purpose to be more fully stated hereinafter.

Cabinet 15 is further provided with registering mechanism 21, for tallying and 65 recording the scores made by the players, and with a ball rebounding surface 22, and ball collecting slopes 23, a ball limiting and retaining mechanism 24, and an initial solenoid 25, for releasing the ball limiting 70 mechanism, to permit a certain number of balls to be played under certain definite conditions, as, for example, when the mechanism is used commercially and the 75 balls are released for play by a coin in the manner stated below.

The movable pocket element 16 may assume any desired shape or size, and in my preferred form the same comprises a rectangular member sloping towards the player and having a suitable number of pockets 26, 27, 28, 29 and 30. These pockets are of varying extent and are so arranged that the easiest and most accessible pocket is nearest the player. This pocket is given 80 the lowest score value. Each succeeding pocket is more difficult, and is given a correspondingly higher score value. The score values are indicated by the registering mechanism 21, on a score dial 32, by pointer 85 33, or equivalent.

Each pocket is provided with an opening 26', 27', etc., through which the ball passes when thrown, or tossed, into any corresponding pocket. Below the several openings there are provided the contactors 26'', 27'', etc., for putting into operation the 95 circuit closers 20, thereby recording the scores of the discarding balls as they roll down the inclined base support 34, and tip the contactors for closing the circuits. From this construction it is evident that balls from the lowest pocket will strike only one contactor, and, therefore, record only one score; those in the next higher pocket will strike 100 two contactors, and, therefore, record two scores, and so on to the highest or last pocket from which the balls will strike all 105

of the contactors and thus close all the circuit closers for recording the proper scores in the manner stated.

A reciprocating mechanism 35, operated by motor 17, causes the pocket to move back and forth within definite limits, thus putting the players' skill to a more severe test.

The ball may be put into play by hand, or by the mechanism illustrated in Fig. 1. 10 If the ball projecting device 18 is used, the same may be put into operation by an operating lever 36. This lever may be supported on a suitable stand or counter 37, and is connected to the projection member 18, 15 by any suitable means as connections 38, which may be united by lever arms 39. A coin chute 40, having electric contacts 41 and 42, may be provided for putting the apparatus into play by insertion of a coin 20 43.

The ball limiting and detaining mechanism 24, comprises a wheel which is provided with a number of radiating spokes or ball stops 44, and a wheel stop 45 for abutting 25 against the end of a stop lever 46. This lever is mounted to swing on a pivot 47, and is controlled by the solenoid 25. Normally, one of the ball stops or spokes engages a detent on the detent lever 48. In 30 the ball limiting form illustrated, six ball stops and one wheel stop are provided, but obviously other numbers might be selected and adopted. Since but one wheel stop is provided for any desired number of ball 35 stops, and a coin releases the wheel stop, it follows that with each release made as many balls may be played as there are ball stops on the detaining mechanism between the wheel stops, and when this number has 40 been played, the ball limiting mechanism will lock against further rotation until the solenoid lever is again moved aside by a coin or other means, to disengage the wheel stop.

The operation of my device may proceed 45 as follows: When a coin is dropped into chute 40, and the circuit closed at 41 and 42 by means of coin 43, current from a suitable source, as a battery 49, passes through conductor 50, solenoid 56, conductor 51, 50 contact 42, coin 43, contact 41, conductor 52, to ground 53. This energizes solenoid 56, which pulls down the score stop lever 57, thus permitting the score wheel bell crank or detent 58 to tilt back and disengage the 55 score wheel 59, which then runs back to the 0 position and stops by reason of the detent engaging stop 31' locking against the detent projection 58'. When a coin thus closes the coin circuit, solenoid 25 is also 60 energized and lever 46 is pulled down by the core 25'. This disengages the wheel stop 45, and releases the ball limiting mechanism 24, which on account of the weight of a ball in position, rotates and permits 65 the ball to descend into playing position in

the projection tray 18. In the meantime detent lever 48 descends and engages the next spoke or ball stop, thus holding the ball limiting mechanism against further rotation until a ball has been played, or is in position 70 to again release detent 48 for succeeding plays.

When the ball is in position on the projection tray, it may be put into play by hand, if desired, or by the mechanism described above. In the latter case the player strikes knob 55 a suitable blow at the exact moment to project the ball into one of the pockets, and preferably into the upper or highest tallying ones. If the ball is successfully landed into the upper pocket 30, it passes through opening 30', tilting contactor 30'', and thereby closing contacts at 20 to complete circuit 50 through solenoid 60, conductor 61, through 30'', 20 and to ground 62, thus energizing solenoid 60 and rocking score detent 58 to advance the score wheel one point. As the ball rolls down the incline 34, it successively tilts contactors 29'', 28'', 27'', 26'', and closes the respective contacts, thus advancing the score wheel for each contact in the manner stated above, and which condition is indicated on the score dial 32. If pocket 26 is hit, only one contact is made. For the intermediate pockets the corresponding contacts are made and recorded and when the ball passes beyond the moving pocket, it rolls down base 19 without making a score.

The score wheel may be provided with 100 any desired number of score contact pins 63, which may be arranged on said wheel in any desired ratio to that of the escapement teeth 67. In the accompanying drawing I have illustrated a ratio of 1 to 2, but 105 obviously other ratios may be adopted. In all cases, however, are the contact pins so located as to close the coupon circuit 64 at 64' at the proper time. The coupon solenoid 65 is thus energized for each specified 110 number of score contacts made. When now the predetermined score contacts have been made to advance the contact pins successively into circuit closing position, current passes from battery 49 through the coupon solenoid 65 in the coupon circuit 64, through 115 the score stop lever 57, contact 57', contact 64', pins 63 to ground 63, thus rocking the coupon detent 70 to advance the coupon wheel one point.

When a predetermined number of balls have been played to again lock the limiting mechanism by reason of engagement between the wheel and stop 45 and the solenoid stop lever 46, a coin inserted in the slot 120 will again release said mechanism in the manner aforesaid. The score wheel will thereupon turn back to zero, but because of the break in the coupon circuit, by reason of lever 57 being depressed, the coupon 125

wheel will not be affected as solenoid 65 is not energized.

The operation of the coupon wheel 68 is similar to that of the score wheel, and the construction of these wheels is identical, excepting that but one contact pin 69 is provided on the coupon wheel. If now the coupon wheel has advanced by reason of the solenoid 65 having, in response to the scores made, rocked the coupon detent 70 the required number of times to rotate the wheel into contacting position of pin 69 with contact 71, the circuit through a bell armature 72 is completed, and the bell begins to ring. The ringing may begin when the coupon wheel approaches or reaches its maximum rotation. Push button 73 may now be used to reset the coupon wheel to zero, and to stop the bell from ringing, because when the circuit is completed through the push button or its equivalent, solenoid 74 is energized to depress lever 75, and thereby interrupt the bell circuit at 76. As lever 75 is depressed, the coupon detent rocks back and permits the coupon wheel to turn back to zero. Should contact be maintained between pin 69 and contact 71, while the coupon wheel is turning back, the bell will not continue to ring as soon as the bell circuit is interrupted by reason of lever 75 being depressed or pulled down, by the core of the solenoid 74.

The recording mechanism may be operated by any suitable means, as by weights 77 and 78, or equivalents, and through proper mechanism (not shown) engaging cogs 79. As this mechanism forms no part of my invention it is not herein shown or described in detail.

Having now described my invention, and disclosed a mode of its application, what I claim as new and useful, of my own invention, and desire to secure by Letters Patent, is:

1. In a game apparatus for playing ball and registering the score made, the combination of a cabinet having moving pocket units therein, a ball tossing mechanism in said cabinet, and means for causing the tossing mechanism to become effective to thereby place a ball into play for registering a score made by passing a ball through any one of said moving pocket units.

2. In a game apparatus for playing ball and registering the score made, the combination of a cabinet having moving pocket elements provided with open sides and bottom for influencing the score value, a ball tossing device in said cabinet, means for operating said ball device, and means for recording the corresponding score value.

3. In a game apparatus for playing ball and registering the score made, the combination of a moving pocket element, a ball control mechanism, means for releasing said

mechanism, means for playing said ball through said moving pocket element to effect a predetermined score, and means for recording said score.

4. In a game apparatus, a cabinet having an open face, a moving pocket element exposed through said face, means for reciprocating said pocket element, a ball retainer and means for releasing a predetermined number of balls from said retainer. 70

5. In an amusement apparatus for playing ball and registering a score made, a cabinet having vertical sides provided with slots therein and an open face, a pocket element reciprocating in said slots and exposed through said face, pockets in said element, means for projecting a ball, said means being under control of the player, for striking one of said pockets, and means associated with each of said pockets for effecting a 80 score. 85

6. In an amusement apparatus for playing ball and registering a score made, a cabinet having vertical sides provided with slots therein and an open face, a sloping pocket 90 element reciprocating in said slots and exposed through said face, a plurality of false-bottom pockets arranged side by side in said element, contractors associated with each pocket, said contractors being arranged beneath corresponding pockets on an incline whereby one or more of said contractors are struck by the same ball passing down the incline from the pocket through which the ball has passed. 95

7. In an amusement apparatus for playing ball and registering a score made, a cabinet, a moving pocket element in said cabinet, said pocket element having a plurality of pockets, a motor element in said cabinet 100 for reciprocating said pocket element, a ball restraining mechanism adjacent said pocket element, an electric control device for releasing said restraining element, means for projecting said ball in the direction of the moving pocket element, whereby, when said ball passes through a pocket, the score value of said pocket will be indicated, and means for indicating said score value. 105

8. In a ball playing apparatus, a moving pocket element comprising a plurality of false-bottom pockets arranged to represent different score values, a sloping base beneath said pockets, an electric circuit with a circuit closer for each pocket projecting in the path of the ball, means for putting a ball into play for passing through one of said pockets, and closing one or more of said circuit closures in conformity with the specific pocket through 115 which the ball passes and then rolls away down the sloping base. 120

9. In an amusement game apparatus provided with ball driving mechanism and score registering mechanism, a cabinet and a 125 130

pocket element therein, a ball operating mechanism in said cabinet, and a manually manipulated member located outside of said cabinet for projecting the ball within the cabinet.

said moving pocket element for supplying a predetermined number of balls to be played into said moving pocket element.

10

In testimony whereof I have hereunto set my hand on this 23rd day of October A. D., 1922.

10. A moving pocket element and means for moving said element, means adjacent

MONNOSUKE HIGUCHI.
